UNITED STATES PATENT OFFICE

HYMAN C. BERKOWITZ, OF BOSTON, MASSACHUSETTS, ASSIGNOR TO BEN-BURK, INCORPORATED, OF BOSTON, MASSACHUSETTS, A CORPORATION OF MASSACHUSETTS

DESIGN FOR A BOTTLE OR SIMILAR ARTICLE

Application filed October 10, 1932. Serial No. 45,285. Term of patent 14 years.

To all whom it may concern:

Be it known that I, HYMAN C. BERKOWITZ, a citizen of the United States, residing at Boston, in the county of Suffolk and State of Massachusetts, have invented a new, original, and ornamental Design for a Bottle or Similar Article, of which the following is a specification, reference being had to the accompanying drawing, forming a part thereof.

In the drawing:

Figure 1 is an elevational view showing one side of a bottle or similar article of my design.

Fig. 2 is a similar view, but with the bottle turned through an angle of 45 degrees to present one corner of the article centrally of said view.

Fig. 3 is a top plan view.

I claim:

The ornamental design for a bottle or similar article substantially as shown.

Signed at Boston, in the county of Suffolk, and State of Massachusetts, this 28th day of September, 1932.

HYMAN C. BERKOWITZ.
